DISAPPEARING WALL CABINET BOARD

Lawrence Romaine Young, Seattle, Wash.

Application July 3, 1935, Serial No. 29,628

2 Claims. (Cl. 38—127)

This invention relates to disappearing wall boards or tables and cabinets for the same and the primary object of this invention is to provide a disappearing wall board or table and cabinet therefor which are adapted for installation in a wall of ordinary thickness, and in which provision is made for inserting or withdrawing a relatively long board or table through a relatively short opening or doorway in the wall, which opening or doorway is positioned at the upper portion of the cabinet.

The invention is shown and described in this application as embodied in a disappearing or wall type ironing board, but said invention is also applicable to wall tables or to any other article or piece of furniture capable of disappearing within a wall space of relatively shallow depth.

Another object of this invention is to provide a disappearing wall board or table which drops down when it is folded into a vertical position within a cabinet and raises up when it is withdrawn from the cabinet and extended into a substantially horizontal position for use, thus economizing on vertical space and effecting a substantial saving in the cost of doors and casings required for the doorway which affords access to the cabinet.

Another object of this invention is to provide a wall board or table which is simple and strong in construction, reliable and efficient in operation and not expensive to manufacture.

A more specific object of this invention is to provide, in connection with a wall or disappearing ironing board, a sleeve board of very simple and efficient construction.

Other and more specific objects of the invention will be apparent from the following description taken in connection with the accompanying drawing.

In the drawing, Figure 1 is a front elevation of an ironing board cabinet and ironing board constructed in accordance with this invention as the same may appear before installation in a wall, the ironing board being shown in an upright position as it may appear when folded into the cabinet.

Fig. 2 is a vertical mid-section of the same, showing the cabinet in a wall, fragments only of the wall being shown and the board being in a folded position within the cabinet.

Fig. 3 is a vertical mid-section similar to Fig. 2, showing an intermediate position through which the ironing board must pass as it is being inserted into or withdrawn from the cabinet.

Fig. 4 is a vertical mid section similar to Figs.

2 and 3 except that it shows the ironing board and sleeve board both extended for use, parts of the ironing board and sleeve board and cabinet being broken away.

Fig. 5 is a cross section on broken line 5—5 of Fig. 1.

Fig. 6 is a detached fragmentary plan view of the base end portion of a sleeve board embodied in the invention.

Fig. 7 is a fragmentary view of a front cross piece for the cabinet said cross piece being dovetailed into the cabinet sides.

Fig. 8 is a fragmentary sectional view, with parts in elevation of a vertically adjustable ironing board.

The drawing shows an ironing board 10 provided near its inner end portion with a rigidly attached cross piece 11. The cross piece 11 has cylindrical pins or studs 12 projecting outwardly from the ends thereof. Said pins 12 project beyond the edges of the board 10, Fig. 5.

The cabinet for the ironing board 10 comprises two upright side members 13 and 14 rigidly connected at their upper ends by a cross piece 15. Another cross piece 16 is rigidly secured to the cross piece 15 and facilitates securing the upper end portion of a cabinet to a wall. The lower end portion of the side members 13 and 14 may be secured to a floor plate 17 at the time the board and cabinet are installed in a building, the plate 17 being a standard part of the ordinary frame building and being positioned substantially at the floor level.

Two strong cross pieces 18 and 19 are rigidly secured to the side members 13 and 14 intermediate the length of the cabinet, preferably nearer to the top than to the bottom of said cabinet. Cross piece 17 extends across the front of the side members 13 and 14 and the cross piece 18 extends horizontally across the cabinet at the rear of said side members 13 and 14. The edges of the side members 13 and 14 are notched for the reception of both of the cross pieces 17 and 18, thus providing a very strong and rigid construction which will resist the lever action of the board 10 in vertical directions, as hereinafter explained. For an ordinary ironing board or table, the height of the upper edge of the front cross piece 17 above the floor plate will usually be about thirty-five inches. The rear cross piece 18 is positioned slightly higher than the cross piece 17, the plane of the lower edge of the rear cross piece 18 being a distance substantially equal to the thickness of the board 10 above the plane of the top edge of the front cross piece 17.

The upper portions of the side members 13 and 14, from the front cross piece 17 to the upper ends thereof, are wider than the lower portions of said side members. This difference in width 5 is approximately three quarters of an inch. This provides room for lath and plaster 20, or equivalent interior wall material, which extends across and covers that portion of the cabinet below the front cross piece 17 after the cabinet is 10 completely installed. Above the front cross piece 17, the plaster or similar interior wall part may be flush with the front edges of the side members 13 and 14. The opening which is left above the cross piece 17 forms a relatively short door- 15 way of substantially shorter length than the cabinet at the upper portion of the cabinet. The usual casing 21 may be provided around the doorway which is formed above said cross piece 17 and a door 22 may be provided for closing said 20 doorway. In Fig. 2 this door is shown in a closed position and is cross sectioned. In Figs. 3 and 4 said door is shown in an open position and is partly broken away.

The inner sides of the side members 13 and 25 14, below the rear cross piece 18, are provided with upright grooves 23 and 24 which serve as trackways for the reception of the pins 12 on the ends of the cross piece 11 of the board 10. In the drawing I show these grooves 23 and 24 30 as extending from the lower ends of the side members 13 and 14 upwardly to approximately the level of the bottom edge of the rear cross piece 18. Obviously, for a shorter board or table, these grooves would not need to extend 35 entirely to the bottom of the side pieces 13 and 14.

For ironing boards and cabinets, made for installation in the wall of an ordinary frame house where commercial 2 x 4 inch studding is used, I find that an opening of twenty five inches 40 height between the front cross piece 17 and the top piece 15 is ample to provide for inserting and drawing out a board 10 which is from three-fourths of an inch to one inch in actual thickness.

The board and cabinet will ordinarily be installed at the time a building is constructed and before the plastering is done. The cabinet of an ironing board is narrow enough so that the side frame members 13 and 14 will fit between upright frame members or studding which are spaced 45 apart the distance ordinarily used in wood frame building construction. A thin back member 25, as of cardboard or any other thin material, may be provided on the back of the cabinet if desired, or the back of the cabinet may be left open, as 50 the outside wall 29 of the building will form a closure for the back of the cabinet when the cabinet is installed.

An electrical outlet fixture 26 is preferably provided in the top 15 of the cabinet for connection 60 with the cord of an electric iron.

When the board 10 is not in use it may occupy a substantially vertical position within the cabinet substantially as shown in Figs. 1 and 2. When the board is to be withdrawn from the cabinet, said board is grasped, preferably by inserting the fingers in a recess 27, and is lifted upwardly and pulled outwardly at the same time. With the board 10 positioned back of the front cross piece 17 and the pins 12 in the grooves 23 and 24 65 70 the upper end of the board 10 may be moved outwardly just far enough to clear the casing 21 at the upper end of the doorway, as shown in Fig. 3. As the board 10 is raised beyond the position shown in Fig. 3, the upper portion of said board 75 may be swung outwardly and downwardly until

the board is brought to rest in the substantially horizontal position shown in Fig. 4. When the board 10 is in this horizontal position the rear end portion of said board is engaged beneath the rear cross piece 18, the lower side of the board 5 rests on the front cross piece 17, and the pins 12 prevent forward displacement of the board. The board is thus very firmly and very securely supported in the extended, or horizontal position. When the outer end portion of the board 10 is 10 lifted up the inner end portion of said board will move downwardly in the cabinet and the board may be quickly and easily folded into the cabinet.

I preferably provide a sleeve board 30 for use in connection with this ironing board. This sleeve board 30 is connected by hinges 31 with the rear cross piece 18. The rear end portion of this sleeve board is preferably slotted as better shown in Fig. 6, and the portion 32 which is cut out in slotting said sleeve board is pivotally connected 20 with the sleeve board by a transverse pivot 33. When the sleeve board 30 is lowered into a horizontal position the portion 32 will drop down and form a short leg which rests on the ironing board and helps to support the sleeve board. When the 25 sleeve board is raised into an upright position the leg portion 32 is positioned in the slot in the sleeve board and is out of the way. The hinges 31 may provide enough friction to ordinarily hold the sleeve board in elevated position or a suitable 30 catch or holding means for holding the sleeve board in an elevated position may be provided.

This cabinet and board are very simple and at the same time very strong and substantial in construction. No hardware, except the hinges 35 for the sleeve board and cabinet door, is required where the board and cabinet are made of wood. Only a small door and a minimum amount of casing are required.

The features hereinbefore set forth provide a 40 very inexpensive board and cabinet. They also provide a construction in which the length of the board is much greater than the length of the doorway. For instance, I am able to provide a board fifty-six inches long in a cabinet not exceeding 45 sixty inches in length and to operate this board through a twenty-five inch doorway.

The board 10 is supported entirely by the cross pieces 17 and 18, when it is extended, and has a considerable amount of resiliency due to the form 50 of the support and to the natural resiliency of the board. When pressure is exerted on the board by an iron in the hands of a user this board is resilient and yieldable to such pressure and the board springs back up, along with the iron, as 55 the pressure on the iron is lessened. This resiliency is beneficial in helping to provide an even pressure on the clothes which are being ironed or pressed. Also by supporting the board entirely from one end I provide complete clearance underneath the board facilitating the use of the board, especially for tubular articles which may be placed over the board.

In Fig. 7 I have shown a fragment of an ironing board cabinet having a front cross member 65 17' which is mortised into the side members of the cabinet by a dovetail joint 35. This more firmly anchors the front cross member to the cabinet and helps to prevent said front cross member from being pried off by improper handling of the board in withdrawing and inserting the board.

In Fig. 8 I have illustrated a board and cabinet therefor in which means are provided for supporting the board at different elevations to ac- 70 75

commodate taller or shorter persons or to provide a board suitable for use either by persons standing up or sitting down. In this disclosure 36 is the side member of a cabinet, 37, 38, and 39 are three rear cross pieces positioned in spaced apart relation, one above another. 40, 41, and 42 are notches provided in the front edges of the side member 36, at intervals one above another, and in proper relation with respect to the rear cross members. An adjustable front cross piece is provided for use in any one of the three notches 40, 41, and 42. This cross piece is designated by numeral 43 and it is removably secured in the notch in which it is to be used. Releasable 10 curing means, as screws 44 may be provided for said cross piece. Groove means 23' is provided in the side member 36 for the reception of pin means 12' on a board 10'. The groove 23' is spaced far enough forwardly from the rear cross 20 pieces 37, 38 and 39 to provide clearance for the board 10' when said board 10' is in an upright position or is being extended or folded. Below the rear cross pieces the groove 23' is inclined or otherwise shaped so as to bring said groove 25 closer to the rear of the cabinet at the lower end of said cabinet. By positioning the cross piece 43 in different notches 40, 41 or 42 it is obvious that the board 10' may be operatively supported at different elevations. In the construction shown 30 in Fig. 8, the opening at the front of the cabinet will necessarily extend to a point below the lowermost notch 42. It will be understood that Fig. 8 shows only one side piece 36 with the several notches and grooves therein and that another 35 corresponding side piece will be provided at the other side of the cabinet.

In Figs. 2, 3, and 4 I have shown the side pieces of the cabinet below the front cross piece 17 as made narrower to provide for the lath and 40 plaster wall 20. However, for some uses, this may not be necessary and in Fig. 8 I have not so narrowed the side member 36.

While I have shown the cabinet and board as made of wood, it will be understood that either 45 or both of the same may be made of metal or of any other material suitable for such purpose.

The foregoing description and accompanying drawing clearly disclose a preferred embodiment of my invention, but it will be understood that this disclosure is merely illustrative and that numerous changes may be made within the scope 50 and spirit of the following claims.

I claim:

1. In apparatus of the class described, a relatively shallow upright wall cabinet adapted to be positioned within a wall between an outer wall member and an inner wall member, said cabinet having a doorway in its upper portion substantially shorter than said cabinet; a disappearing board member of substantially greater length 55

than said doorway and less length than said cabinet movable through said doorway into and out of said cabinet; a cross member secured to the under side of said board adjacent the rear end portion of said board; two upright side members for said cabinet; two oppositely faced vertical guide slots in said side members adjacent the rear wall of the cabinet; a guide pin protruding from each end of the cross member on the board into the adjacent guide slot, said guide 10 pins guiding the lower end portion of said board member for vertical movement in said cabinet; a horizontal front cross piece rigidly connected with the front portion of said cabinet at the location of the bottom edge of said doorway; 15 and a horizontal rear cross piece rigidly connected with the back portion of said cabinet, the bottom of said rear cross piece being spaced above the plane of the top of said front cross piece a distance substantially equal to the thickness of said board, said board being movable between said two cross pieces and said board resting on the front cross piece and engaging beneath the rear cross piece when said board is in a substantially horizontal extended position, said guide 20 slots being positioned below said rear cross piece and extending from the plane of the bottom of said rear cross piece substantially to the bottom of the cabinet.

2. In wall cabinet means for installation between the outer and inner portions of a wall, which outer and inner wall portions are spaced apart by standard two by four inch studding; a wall cabinet of shallow depth positioned between said inner and outer wall portions, said 25 wall cabinet having a doorway in its upper portion substantially shorter than said cabinet; a disappearing board member of substantially greater length than said doorway and slightly less length than said cabinet movable through 30 said doorway into and out of said cabinet; groove and pin means guiding the lower end of said board member for vertical movement in said cabinet; a horizontal front cross piece adjustably and rigidly connected with the front portion of 35 said upright side members, said side members having notches at a plurality of elevations receiving said cross piece; and a plurality of horizontal rear cross pieces rigidly connected with the rear portion of said upright side members, the bottom of each of said rear cross pieces being spaced above the plane occupied by the top of said front cross piece for each location provided by said notches a distance equal to the thickness of said board, whereby the board will rest on the top 40 of said front cross piece and engage below one of said rear cross pieces for each vertical position of the board.

LAWRENCE ROMAINE YOUNG. 60
